SAID GEORGE C. HERREN, DECEASED, ASSIGNOR TO ELLA P. HERREN, OF ATLANTA,
GEORGIA

DISPLAY STAND

Application filed July 18, 1930. Serial No. 468,908.

This invention relates to supporting structures adapted to display merchandise, and more especially to a rack or stand so equipped as to readily receive and support a plurality of sealed bags made up of transparent paper, such as cellophane, it being understood that the bags may contain any edible commodity, such as salted peanuts, or any other article which it is desired to be submitted for inspection and at the same time protected from the atmosphere, and from dust and handling.

The cellophane bags or receptacles at present on the market are somewhat delicate in structure and of more or less brittle consistency, so that if a plurality of filled bags are laid in a box, one upon the other, the cellophane wrapper will be very liable to become broken in certain of the bags, thereby permitting the air to destroy the freshness of any edible commodity therein contained, or to subject the imperfectly enclosed article to the deleterious effects of dirt, dust, and handling by customers.

It is therefore the primary object of the present invention to seal each end of the bag described by means of a rigid member, and to secure to one of said members a tab which adapts the bag to be suspended upon a support where it will be out of contact with any other bag.

Other objects of the invention will be made apparent in the following specifications, when read in connection with the drawings forming a part thereof.

In said drawings:

Fig. 1 is a perspective view of a stand provided with a plurality of slots adapted to receive a projecting tab carried by the bag, and,

Fig. 2 is a side elevation of said stand on a slightly enlarged scale, the base of the stand not being shown, and the top in partial section.

Now referring specifically to the drawings, in which like reference numerals indicate like parts throughout the several views, 1 indicates the body of a stand which is here shown as rectangular in cross section, and 50 having an enlarged base 2 and a truncated top

3 axially perforated to receive a staff 4, bearing an advertising card 5.

The stand is adapted for the support of one or a plurality of bags made up of cellophane, or other transparent material, and, with this end in view, is here shown as provided on each of its lateral faces with a plurality of equally spaced inwardly and downwardly inclined slots 6, of a length and width adapted to correspond to the measurements of a suspension tab 7, held in a clip 8, which closes and seals the end of the bag 9, as shown best in Fig. 2.

It is to be noted that each of the slots 6 extends entirely across each face 10 of the stand 1, and also through the face 11 at right angles to said face 10, it being observed however, that the side 12 of certain slots terminate just short of the slot 6 immediately thereunder, as shown in Fig. 2, or may terminate substantially above the top of the slot 6, as shown in Fig. 1, the purpose of this structure being to prevent interference of a tab in the slot 6 on one face, with a similar tab in a slot 6 on an adjacent face. Such interference would be unlikely in any event however, since the width of the tabs 7 are preferably slightly shorter than the lateral dimensions of the slots 6.

If desired, the stand 1 may be rotatively mounted on the base 2, by the provision of a pin 13, shown in dotted lines in Fig. 1, which pin may fit into a socket in the top of the base.

From the foregoing it will be manifest that I have provided a stand upon which bags of this character may be displayed without danger or rupture, and in plain view of the prospective purchaser. Ordinarily a customer will remove the top bag on the nearest side of the stand, not touching any of the other bags.

While I have shown and described a stand which is rectangular in cross section, it is of course understood that a stand of cylindrical or other cross section could be adapted to this use. Modifications of the structure herein disclosed may be suggested to those skilled in the art, but my invention includes all embodiments.

ments falling fairly within the scope of the appended claim.

The cellophane bag structure, with its end closures and connected supporting tab, is covered by my companion application, Ser. No. 468,909, filed of even date herewith.

I claim:

A display stand comprising a rectangularly formed upright having a plurality of vertical rows of downwardly and inwardly inclined parallel slots formed in the faces thereof, each slot of each row extending entirely across a face of the upright and into the adjacent faces on each side thereof, and terminating short of the top edge of a horizontal slot formed in each adjacent face of the upright.

In testimony whereof I hereunto affix my signature.

GEORGE C. HERREN.
